UNITED STATES PATENT OFFICE.

GEORGE DORELL COOPER, OF ST. JOHNS, MICHIGAN, ASSIGNOR OF ONE-HALF TO SEYMOUR D. WATSON, OF ST. JOHNS, MICHIGAN.

STEAM-GENERATOR.

SPECIFICATION forming part of Letters Patent No. 738,526, dated September 8, 1903.

Application filed July 1, 1902. Serial No. 113,959. (No model.)

To all whom it may concern:

Be it known that I, GEORGE DORELL COOPER, a citizen of the United States, residing at St. Johns, in the county of Clinton and State of Michigan, have invented certain new and useful Improvements in Steam-Generators, of which the following is a specification, reference being had therein to the accompanying drawings.

10 The invention has particular reference to a water-tube boiler; and it consists in the novel construction thereof and in the peculiar arrangement and combination of its various parts, as will be more fully hereinafter described, and shown in the drawings, in which—

Figure 1 is an elevation of the boiler. Fig. 2 is a vertical central longitudinal section therethrough, and Fig. 3 is a vertical cross-section.

20 Briefly described, the reference-letter A designates the steam-drum of the generator, which is preferably cylindrical in configuration and of any approved construction.

B is the usual dry-pipe therein, apertured 25 upon its top, as shown, and having an exit C, leading to and through the boiler-top.

As illustrated, the drum is supported upon a vertical water-wall D, the wall being of greater width than the diameter of the drum 30 and supported in turn by a framework E upon each side of the drum and supporting feet or brackets F. As shown, the water-wall is recessed or arched at its lower portion, forming two vertically-depending spaced water-legs G 35 and H, extending in proximity to the base of the framework.

I designates a plurality of water-tubes projecting from the opposite sides of the water-wall and also from the two water-legs, as 40 shown. These tubes are closed at their outer ends by plugs a, which are fitted tightly within the pipe ends and are squared. The opposite or inner ends of the tubes are threaded and adapted to be screwed within openings

45 formed within the water wall and legs, as shown in the drawings. For the purpose of allowing the water to drain from the pipes into the water-wall and the water-legs communicating therewith the groups of pipes

50 upon the opposite sides of the wall and legs are inclined slightly vertically. The water-

wall in turn communicates at its upper end with the steam-drum, so as to permit of a circulation through the drum, the water-wall and depending legs, and the pipes or tubes. 55

By arching the water-wall and arranging the water-tubes therein in the manner set forth it will be observed that a fire-chamber J is formed by the tubes which extends uninterruptedly beneath the drum its entire 60 length. Thus a maximum amount of heating-surface is produced for the boiler and the efficiency of the apparatus is materially increased.

K represents the ordinary grate-bars arranged in the fire-chamber, and L designates the main steam-pipe connected to the dry-pipe previously referred to and preferably coiled about the drum in close proximity thereto, as illustrated. 65

M designates an outer metallic casing which incloses the entire apparatus with the exception of the brackets and framework E, and O is a smoke-pipe leading from the casing through which the products of combustion 70

75 pass. The casing described forms a combustion-chamber about the water-tubes, the drum, and the coil portion of the main steam-pipe, so that the steam is superheated and becomes 80 dry, whereby a large amount of water that in other generators is usually carried off by the steam is retained in the boiler. The water-tubes are secured within the water-wall and the depending legs in a manner to leave 85 spaces therebetween for the circulation of the flame and the gases of combustion, the latter passing upwardly between the tubes and also within the combustion-chamber about the tubes to the stack. The free end of the main 90 steam-pipe projects through an opening b in the front of the casing M, permitting proper connections to be made between it and the engine.

For the purpose of cleaning the generator 95 valve-controlled blow-off pipes A' are employed, leading from the bottom of each water-leg. These pipes are preferably four in number, extending from the opposite sides of the legs in a manner similar to the water-tubes and projecting through the casing ends, the valves B', as shown, being without the cas-

ing where access may be readily had thereto when it is desired to clean the apparatus.

What I claim as my invention is—

1. In a steam-generator, the combination with the steam-drum, of a vertical water-wall beneath and communicating with the drum, the wall having its lower portion arched forming two spaced water-legs, a plurality of water-tubes projecting in the direction of the drum from the opposite sides of the water wall and legs forming a fire-chamber extending uninterruptedly beneath the drum its entire length, said tubes being closed at their outer ends and communicating at their inner ends with the water-wall, and a casing inclosing and forming a combustion-chamber about the tubes, water-wall and drum.
2. In a steam-generator, the combination with the horizontal steam-drum, of a vertical water-wall forming a central support for and

communicating with the drum, said wall having its lower portion arched forming two spaced water-legs, a plurality of parallelly-arranged water-tubes projecting from the opposite sides of the water wall and legs forming a fire-chamber extending uninterruptedly beneath the drum its entire length, said tubes being closed at their outer ends and communicating at their inner ends with the arched water-wall, and an outer sheet-metal casing, provided with a stack, inclosing and forming a combustion-chamber about the tubes, water-wall and drum.

In testimony whereof I affix my signature in presence of two witnesses.

GEORGE DORELL COOPER.
